NECKTIE

Frederick P. Muhlhauser, Rochester, N. Y., assignor, by mesne assignments, to Superba Cravats, Rochester, N. Y., a copartnership consisting of Herman M. Cohn, Julian Wiley, Sr., Harold Shriner, Harry S. Cohn, Irving Lerner, Julian Wiley, Jr., H. W. Lewine, and said Muhlhauser

Application August 30, 1940, Serial No. 354,845

12 Claims. (Cl. 2—146)

1

This invention relates to four-in-hand neckties:

It is the main object of the present invention to provide an improved four-in-hand necktie having a lining member which will cause the necktie to drape attractively when tied in the usual manner.

It is a further object of the invention to provide a lining member that will not create unsightly bulges in the necktie when the necktie is displayed on a store counter and which will cause a major portion of the gathered material resulting in and immediately below the knot when the necktie is tied, to fall into a single central crease or dimple.

These and other objects of the invention will appear from the detailed description and claims when taken with the drawing in which:

Fig. 1 is a perspective view of a four-in-hand necktie made in accordance with the present invention, a portion of the front face of the necktie envelope being broken away to show the construction of the modified lining member;

Fig. 2 is a fragmentary front view of the necktie of the present invention illustrating the drape effect obtained when the necktie is tied;

Fig. 3 is a transverse section through the wide or tying end of a necktie made in accordance with the present invention, the section being taken on a line corresponding to line 3—3 of Fig. 1;

Fig. 4 is a transverse section taken substantially on the line 4—4 of Fig. 2;

Fig. 5 is a front face view of a portion of the wide end of a lining member used in the necktie of the present invention, and illustrating an intermediate stage in the manufacture thereof;

Fig. 6 is a view similar to Fig. 5 but showing the completed lining member ready to be enclosed in a necktie envelope of conventional construction;

Figs. 7 and 8 are views corresponding to Figs. 5 and 6 respectively but illustrating a modification of the invention;

Figs. 9 and 10 are views corresponding to Figs. 5 and 6 respectively but illustrating another modification of the invention;

Figs. 11 and 12 are views corresponding to Figs. 5 and 6 respectively illustrating still another modification of the invention;

Fig. 13 is a transverse section taken substantially on the line 13—13 of Fig. 6;

Figs. 14 and 15 are transverse sections taken on a line corresponding to line 13—13 of Fig. 6 and illustrating the progressive deformation that occurs in the lining member in and immediately

below the necktie knot as the necktie is being tied; and

Fig. 16 is a transverse section taken substantially on the line 16—16 of Fig. 8.

Referring to the drawings and particularly to Fig. 1, there is shown a four-in-hand necktie generally indicated 5 comprising a tie envelope 6 having a lining member 7 enclosed therein. The lining member may be made of the usual fabrics employed for necktie linings and preferably extends throughout substantially the entire length of the necktie envelope. The envelope 6 and lining member 7 are preferably cut on the bias to provide a resilient construction.

15 The necktie envelope may be made of the usual tie fabrics and finished in the usual manner. However, it is proposed to modify the lining member 7 so that the tie will automatically crease or dimple concavely along a central longitudinal line 20 in the front face thereof at the knot region when tied as shown at 8 in Figs. 2 and 4.

In Fig. 5 where a fragment only of the resilient or elastic lining member 7 is shown, it will be noted a pair of resilient strips 9 of bias-cut 25 fabric or other elastic material are laid flat on the lining and stitched or otherwise suitably secured at their ends to the lining as indicated at 10. These resilient or elastic strips are then spread apart between their fixed ends as shown 30 in Fig. 6 and secured in this stressed condition to the lining 7 as by the stitching 11. If desired instead of using stitching 10 and 11, the strips 9 may be secured to the lining member by any suitable means such as by an adhesive.

It will be understood that the strips 9 are resilient and therefore tend to assume the straight condition shown in Fig. 5. Consequently since the strips are stressed laterally when secured to the lining member in the manner described above 40 they will tend to bow the lining 7 slightly. This bowing produces a very slight concavity in the front face of the lining but which is so slight that it does not interfere with the flat appearance of the necktie when displayed on a store counter. However, when the necktie is stressed longitudinally as when pulling the knot of the necktie tight the strips 9 substantially straighten out and increase this bowing effect and cause the lining 7 to crease or dimple between the strips as shown at 12 in Fig. 14. The tendency for the lining member to crease in this manner is further increased by the constrictive force exerted by the knot of the tie as it decreases in size to compress the front end of the tie which 50 extends through the knot. Since the lining will

already have begun to bow or crease between the strips 9, the further creasing action by the knot will also be localized between the strips. When the necktie has been tied the lining will have been deformed into the shape substantially shown in Figs. 4 and 15, the rearwardly curved portions 13 resulting from the fact that the lining is so much wider than the width of the knot that a portion of the edges of the lining may be turned toward the back of the knot. The front face of the tie envelope will follow the crease in the lining member so that it will have a corresponding crease or dimple therein similar to the lining member as best seen in Figs. 2 and 4.

In Figs. 7 and 8 there has been shown a slightly modified form of the invention. Instead of using the rectangular strips 9, resilient strips 15 are provided which have a concave outer edge 16 (Fig. 7). The strips 15 are first laid flat on the lining member and secured thereto along their ends in any suitable manner as by adhesive or stitching 17 (Fig. 7). The strips are then pulled laterally until their concave edges 16 are alined with the side edges of the lining member 7 as shown in Fig. 8. Longitudinal stitching or the like 18, maintains the strips 15 in this laterally stressed position on the lining 7. It will be noted that as a result of the lateral stressing of the strips 15 the normally straight edges 19 (Fig. 7) are now curved (Fig. 8) and provide a space therebetween which is equivalent to the spacing between the strips 9 (Fig. 6). The lining member shown in Fig. 8 is adapted to be incorporated in a necktie envelope 6 and will cause the necktie to crease or dimple in the manner previously described.

The modification illustrated in Figs. 9 and 10 is similar to that shown in Figs. 7 and 8 except that the strips are in effect only partially divided by the slit 20. In this modification a single resilient or elastic piece of material 21 having concave edges 22 and a longitudinal slit 20 is secured to the lining member 7 in a manner similar to that described above. The piece 21 is first laid flat on the lining 7 (Fig. 9) and secured thereto at its ends as indicated at 23. The piece 21 is then stretched laterally to bring the concave edges 22 into alinement with the edges of the lining 7 and secured thereto as indicated at 24 (Fig. 10).

To simplify the manufacture of the piece 21 it will be appreciated that the slit 20 may extend to one end of the piece if desired so that the slit may be made by means of scissors or the like, inwardly from one end.

The same creasing or dimpling effect of the tie can be obtained by cutting the lining member in the manner illustrated in Fig. 11. In the knot region of the tie the opposite edges of the resilient lining member 7a are cut out as shown at 25 and a central slit provided as indicated at 26. A resilient piece 27 which may be slightly longer than the slit 26 and having tapered side edges 28 which form a continuation of the tapered side edges 29 of the lining member when superposed thereon is suitably secured to the under side of the lining as indicated at 30 in Fig. 11. The lining member 7a is then stretched laterally to bring the concave edges 25 into alinement with the straight edges of the lining member as shown in Fig. 12 and secured to the piece 27 as indicated at 31. This modified lining member will crease or dimple in the same manner as the previously described lining members although it will be understood that the crease will form in the piece 27.

While the invention has been described in de-

tail it will be appreciated that various modifications of the invention will occur to those skilled in the art and these modifications falling within the scope of the claims are to be considered a part of the present invention.

What I claim is:

1. A necktie comprising a necktie envelope, a lining member enclosed within said envelope, said lining member having a member of elastic material secured to one face thereof, one of said members including strip-like sections secured to the remaining member at spaced points with the sections at said spaced points adjacent each other, the portion of said sections intermediate said points being spread apart and secured to said remaining member.
2. A lining for neckties comprising an elastic lining member, means secured to said lining member for causing it to crease when the necktie is tied, said means including a piece of elastic material secured to said lining member at the region to be creased providing two plies of elastic material at said region, one of said plies being divided longitudinally into two parts throughout at least a portion of said region and secured to the other ply with the respective parts thereof curved outward laterally toward the adjacent respective edges of said other ply and then inward with respect thereto.
3. A lining for neckties comprising an elastic lining member, an elastic member including strip-like sections superimposed on said lining member with said sections extending longitudinally therefrom, spaced means for securing the ends of said sections to said lining member with the respective ends adjacent each other, the spacing between said spaced means being substantially equal to the normal length of the portion of said sections between said spaced means, and means for securing the portion of said sections between said spaced means to said lining member in laterally stressed condition.
4. A lining for neckties comprising a bias-cut lining member, bias-cut strips fixed at their ends to one face of said lining member with the respective ends close to each other, the portion of said strips intermediate their fixed ends being spaced apart and secured to said lining member in laterally distorted condition.
5. A lining for neckties comprising an elastic lining member, a piece of elastic material secured to said lining member, said piece being divided substantially centrally thereof throughout at least a portion of its length providing strip-like sections, said sections being fixed in adjacent relation at spaced points to said lining member, the portion of said sections intermediate said spaced points being separated from each other and being secured to said lining member in laterally distorted condition.
6. A lining for neckties comprising an elastic lining member, elastic strips superposed on one face of said lining member and extending longitudinally thereof in generally parallel relation, means securing both pairs of adjacent ends of said strips close together on said lining member, and means extending longitudinally of said strips for securing said strips to said lining member with their intermediate portions spread apart.
7. A lining for neckties comprising an elastic lining member, a piece of elastic material superposed on one face of said lining member, said piece having a slit therein closed at both ends and extending longitudinally of said lining member, means for securing the ends of said piece

to said lining member, the portions of said piece at each side of said slit being spread apart in the plane thereof and means extending longitudinally of said lining member for securing said laterally spread portions to the lining member.

8. A lining for neckties, comprising an elastic lining member, said member having a longitudinal slit therein, a piece of elastic material overlying said slit, means for securing said piece to said member adjacent the ends of said slit, portions of said lining member at each side of said slit being spread apart and secured to said piece.

9. A stage in the method of making a necktie having an elastic lining which comprises superimposing an elastic member on said lining member, at least a portion of one of said members being divided longitudinally, securing said members together at spaced points in unstressed condition, laterally spreading the portion of said divided member between said spaced points to stress the same and securing said portions of said divided member to the remaining member in spread relation.

10. A stage in the method of making a necktie having an elastic lining member which comprises fixing the ends of a pair of elastic strips to one face of said lining member, spreading said strips intermediate said fixed ends and securing said strips to said lining member in spread relation.

11. A four-in-hand necktie constructed so as to present a central dimple directly beneath the knot when tied, comprising in combination an outer fabric envelope having a knot-forming area, and a stretchable liner of bias cut coarse woven fabric enclosed within said envelope, the liner including outer side edges and having a medial elongated aperture midway between said side edges in the region of the knot-forming area of the outer envelope, leaving narrow bias cut disintegrable strips of fabric flanking said aperture, and stretch arresting means carried by the liner at opposite sides of the single aperture in substantially coextensive relationship thereto,

said stretch arresting means being in the form of long lines of stitching disposed in substantial parallelism with the major axis of the elongated aperture, serving also to bind the short threads of the aforesaid narrow strips of fabric which flank the aperture, thereby to preclude disintegration of the narrow strips by separation of their constituent short bias cut threads.

12. A four-in-hand necktie constructed so as to present a central dimple directly beneath the knot when tied, comprising in combination an outer fabric envelope having a knot-forming area, and a stretchable liner of bias cut coarse woven fabric enclosed within said envelope, the liner including outer side edges and having a medial elongated aperture midway between said side edges in the region of the knot-forming area of the outer envelope, leaving narrow bias cut disintegrable strips of fabric flanking said aperture, and stretch arresting means carried by the liner at opposite sides of the single aperture, said stretch arresting means being in the form of long lines of stitching disposed in substantial parallelism with the major axis of the elongated aperture in flanking relationship to said aperture and extended beyond both ends of said aperture, the stitching being in binding relationship to the short biased threads of the narrow fabric strips to preclude disintegration of the strips by separation of their constituent short threads when the liner is subjected to tensile strains.
